US0D1094941S

(12) **United States Design Patent** (10) Patent No.: **US D1,094,941 S**
(45) Date of Patent: ** Sep. 23, 2025

(54) **WASTE RECEPTACLE**

(71) Applicant: **simplehuman, LLC**, Torrance, CA (US)

(72) Inventors: **Frank Yang**, Rancho Palos Verdes, CA (US); **Adam Wade**, Rancho Santa Margarita, CA (US); **Yoon Kim**, Long Beach, CA (US)

(73) Assignee: **simplehuman, LLC**, Torrance, CA (US)

(**) Term: **15 Years**

(21) Appl. No.: **29/864,550**

(22) Filed: **Jun. 3, 2022**

(51) LOC (15) Cl. **09-09**

(52) U.S. Cl.

USPC **D34/9**

(58) **Field of Classification Search**

USPC D34/1, 1.1, 3, 5, 6, 7, 8, 9, 10; D32/37

(57) **CLAIM**

The ornamental design for a waste receptacle as shown and described.

DESCRIPTION

FIG. 1 is a top, front, right-side perspective view of a waste receptacle showing our new design;

FIG. 2 is a bottom, rear, left-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines in the drawings depict portions of the waste receptacle that form no part of the claimed design;

1 Claim, 8 Drawing Sheets
